UNITED STATES PATENT OFFICE.

CHARLES LOFMAN, OF LOS ANGELES, CALIFORNIA, ASSIGNOR TO ROBERTI BROS., A CORPORATION OF CALIFORNIA.

CLOSET OR RECESS BED.

Application filed December 7, 1925 Serial No. 73,585.

Although my present invention may be referred to as a closet bed or a recess bed, this invention relates more particularly to a bed comprising parts which are intended to be permanently secured to the floor, within a closet or recess; and each bed may comprise a tiltable frame, which is adapted to be easily swung or shifted to a horizontal position of use; and it is an especial object of this invention to provide a bed construction, of the general character indicated, such that a bed frame, so mounted as to be easily movable to and from a vertical position, shall be automatically advanced from its closet or recess incidentally to the lowering of the same and shall be automatically retracted into its closet or recess incidentally to the elevation of said frame.

It is an object of this invention to provide a closet or recess bed with special fixed guide rails and connections of such character that, although these rails or guides remain entirely within a closet or recess, they control movements of parts which are advanced from or retracted into said closet or recess; and preferred embodiments of my invention may comprise, in combination with the mentioned fixed guides and tiltable bed frame, an interposed carriage or carriages having a slidable or rolling relationship to said guides and having also a pivotal connection with said bed frame.

Other objects of my invention, including certain novel linkages and connections and involving the use of a slotted tube as a guide rail internally engageable with rollers of a special type, may be best appreciated from the following description of an illustrative embodiment of the same, taken in connection with the appended claims and the accompanying drawings, in which—

Fig. 1 is a front elevational view, with parts broken away.

Fig. 2 is a horizontal sectional view, taken substantially as indicated by the lines 2—2 of Fig. 1.

Fig. 3 is a side elevational view, on a slightly enlarged scale, taken substantially as indicated by the arrow 3 of Fig. 1, with parts broken away.

Fig. 4 is a detail view, on an enlarged scale, taken substantially as indicated by the line 4—4 of Fig. 3.

Referring to the details of that specific embodiment of my invention chosen for pur-

poses of illustration, the floor of a closet or recess being indicated by a full line at 11, whereas side walls and a back wall are suggested by dash lines 12, 12' and 13 (a door or curtain being indicated in Fig. 2 by an additional dash line 14) I show special rails or guides 15, 15' (which may be cylindrical in form and adapted to contain special rollers 16, 16', of the general character separately illustrated in Fig. 4) as secured by angle brackets hereinafter mentioned and I show carriages 18, 18' (each comprising a rear upright or vertical member 19, a front vertical member 20, an upper horizontal member 21 and a lower horizontal member 22) as supported in part from, and adapted to advance horizontally in the planes of, the respective rails or guides 15, 15'.

Each of the carriages 18, 18' (shown as connected by a head or foot frame 23, comprising an over-arching element 24, a lower horizontal element 25 and uprights 26) may be provided with means (such as a bearing bracket 27 provided with an upwardly opening notch 28) for the pivotal support of a bed frame,—such as a bed frame comprising side elements 29, 29' and transverse elements 30. For example, each of the bed frame side elements 29, 29' may have secured thereto, as by means of rivets 31, a bracket 32 (or 32') carrying a pin 33, (or 33') ; and, in order to obviate risk of accidental disconnection, each of these pins may advantageously be provided with an irregularity or head 34, 34',—shown as interfitting within a space 35, (35') provided by offsetting the bodies of the bearing brackets 27 relatively to the terminal portions 36 thereof,—which may be welded or otherwise permanently secured to the upper horizontal elements 21 of the carriage or carriages 18, 18'.

Whether or not the rear uprights 19, 19' of the mentioned carriage or carriages are interconnected in the manner described, the lower front corners thereof may be secured together by means such as a horizontal bar 37, shown as provided with castors 38, 38', adapted to support the front end of the mentioned carriage or carriages during the advance of the same to or from a position such as that indicated in dotted lines in Fig. 3; and the rear or inner ends of the mentioned carriage or carriages may at all times be supported by means of the special rollers 16, 16' interfitting within guides 15, 15' in the general manner separately illustrated in Fig. 4.

In preference to inserting screws directly through the bottoms of the guides 15, 15', (slotted at 39, to permit longitudinal advance of leg brackets 40, carrying the mentioned 5 rollers 16, 16', by means of ball bearings 41, 41') I may fasten said guides in place by means such as angle brackets 42, 42'; and I show the forward brackets 42' as serving also for the pivotal connection of special links 10 43, 43' respectively provided with long slots 44 and with shorter slots 45, the former being engageable by pins 46.

The pins 46, 46', are shown as projecting horizontally from frame elements 47, 47', 15 and these are shown as rigidly secured at right angles to the bed frame side elements 29, 29'. The slots 45 in the links 43 are shown as cooperating with slots 48, in the upper horizontal elements 21 of the carriage or carriages 18, 18' (or in plates 49 secured thereto) 20 in the retention of floating pins 50; and the positions and dimensions of the respective slots 44 and 45 relatively to the cooperating pins 46 and 50 are intended to be such that 25 whenever the upper portion of the bed frame comprising side elements 29 is drawn forward (swinging about the pivot pins 33, 33') this pivotal movement is effective, by a camming action between the pins 46 and 50 relatively to the slots through which these pins extend, to draw the carriage or carriages 18, 18' simultaneously forward toward the dotted line position, Fig. 3 the opposite upward and inward movement of the bed frame being correspondingly effective to retract the mentioned carriage or carriages toward the position in which it is shown in dotted lines. 30 The respective ends of the fixed guides 15, 15' may be closed and strengthened by means such as plugs or caps 51, 51'; and the length of the guides 15, 15' may be such that, during the swinging of the mentioned bed frame between an upright position and a horizontal position, the rollers 16, 16', or their equivalents, advance from contact with the plugs or caps 51' into, or nearly into, contact with the plugs or caps 51'; and it will be noted that 35 the rollers 16, 16', are adapted to contact either with the bottom or with the top of the interior surface of the guides 15, 15' (although not contacting with both the bottom and the top at the same instant), thereby preventing any tilting of the carriage or carriages 18, and compelling the same to move in and out in the general manner described. 40

It will be appreciated that the bed frame comprising the side elements 29, 29' and two or more transverse elements 30 may be equipped with any usual or preferred springs, 45 such as, for example, spiral springs 52, shown as supported therefrom by means of straps 53 and as supporting a subsidiary frame 54. With this they may be connected in any usual or preferred way, as by means of wires 55,-- 55 the use of diagonally extending tension

springs 56 connecting the tops of the conical springs 52, and the use of mattress stops 57, being obviously immaterial to the invention herein described, although illustrated for the sake of completeness.

Any preferred means, not shown, may be used for the retention of a mattress and bedding upon a bed frame pivotally movable in the general manner described; and it will be noted that, incidentally to the advance of the described bed frame and carriage or carriages (whose movements may be facilitated by the interposition of springs 58 between the transverse elements 37, by which the mentioned carriages are interconnected, and the adjacent transverse element 30 of the described bed frame) the head or foot frame 23 is drawn forward; and that the net effect of the interdependent movements described is such as to throw the entire bed frame out of the closet or recess in which the guides 15, 15' may be secured,--so that the occupant of the bed may enjoy a free circulation of air on all sides of and above and below his bed.

Although I have herein described specific embodiments of my invention, it should be understood that various features thereof might be independently employed, and that numerous modifications might be made, by those skilled in the art to which this case relates, without the slightest departure from the spirit and scope of my invention, as the same is indicated above and in the following claims.

I claim as my invention:

1. A bed organization of the general character described comprising a horizontally movable carriage, floor guides for said carriage within a closet or recess, a bed frame pivotally mounted on said carriage and rotatable between a vertical and a horizontal position, and means at each side of said carriage pivotally connected to the floor in a plane substantially in front of the vertical position of said bed whereby a tilting of said carriage causes a relative movement of said carriage with respect to the closet or recess.

2. A bed organization of the general character described comprising a horizontally movable carriage, floor guides for said carriage within a closet or recess, a bed frame pivotally mounted on said carriage and rotatable between a vertical and a horizontal position, and means at each side of said carriage pivotally connected to the floor in a plane substantially in front of the vertical position of said bed, whereby a tilting of said frame causes a relative movement of said carriage with respect to the closet or recess, said carriage having roller means for engaging said guides.

3. A bed organization of the general character described comprising a horizontally movable carriage, floor guides for said carriage within a closet or recess, a bed frame

5 pivotally mounted on said carriage and rotatable between a vertical and a horizontal position, and means at each side of said carriage pivotally connected to the floor in a
10 5 plane substantially in front of the vertical position of said bed, whereby a tilting of said frame, causes a relative movement of said carriage with respect to the closet or recess, and said guides consisting of slotted tubes
15 10 and said carriage having rollers within said tubes.

4. A bed organization of the general character described comprising a horizontally movable carriage, floor guides for said carriage within a closet or recess, a bed frame pivotally mounted on said carriage and rotatable between a vertical and a horizontal position, and means at each side of said carriage pivotally connected to the floor in a
20 20 plane substantially in front of the vertical position of said bed, whereby a tilting of said frame causes a relative movement of said carriage with respect to the closet or recess, and said guides consisting of slotted tubes and
25 25 said carriage having rollers within said tubes, said rollers being adapted to engage alternately either the top or bottom interior surface of said tubes.

5. A bed organization of the general character described comprising a horizontally movable carriage, floor guides for said carriage within a closet or recess, a bed frame
30 30

35 pivotally mounted on said carriage, a slotted link at each side of said carriage having one end pivotally connected to a stationary member adjacent the outer end of said carriage, and means on said carriage and said bed frame cooperating with said link, whereby a tilting of said bed frame causes a relative movement of said carriage with respect to 40
40 said closet or recess, said means including pins on said carriage and frame engaging the slotted portion of said link.

6. A bed organization of the general character described comprising a horizontally 45 movable carriage, floor guides for said carriage within a closet or recess, a bed frame pivotally mounted on said carriage, a slotted link at each side of said carriage having one end pivotally connected to a stationary member, and means on said carriage and said bed frame cooperating with said link, whereby a tilting of said bed frame causes a relative movement of said carriage with respect to said closet or recess, said link having a plurality of slots therein and said cooperating means comprising a pin on said bed frame engaging in one of said slots in the link, and a floating pin engaging in the other slot in
50 50 said link and in a slot formed in said carriage. 60

In testimony whereof, I have hereunto set my hand at Los Angeles, California, this 18 day of November, 1925.

CHARLES LOFMAN.
